UNITED STATES PATENT OFFICE.

MOSES GOLDMAN, OF PITTSFIELD, MASSACHUSETTS.

SPRINKLER AND ATOMIZER.

SPECIFICATION forming part of Letters Patent No. 293,730, dated February 19, 1884.

Application filed May 14, 1883. (No model.)

To all whom it may concern:

Be it known that I, MOSES GOLDMAN, of Pittsfield, in the county of Berkshire, in the State of Massachusetts, have invented new and useful Improvements in Sprinklers and Atomizers, of which the following, taken in connection with the accompanying drawings, is a full, clear, and exact description.

This invention relates to a simple and comparatively inexpensive and very convenient and effective device adapted for throwing fine sprays and for sprinkling clothes, tobacco in manufacture, plants, and for various other useful purposes.

15 The invention is fully illustrated in the annexed drawings, wherein Figures 1 and 2 are side views of two of the forms in which the invention may be embodied, and Fig. 3 is a transverse section of the perforated collapsible or compressible water-receptacle which throws the spray.

Similar letters of reference indicate corresponding parts.

A represents the collapsible or compressible water-receptacle in the form of a hollow rubber ball, provided on one side with perforations *a a*, and on the opposite or upper side with a water-inlet, *b*. Said ball is seated in a ring, *r*, on a holder, *H*, to which latter is 25 hinged a lever, *L*, having directly over the inlet *b* of the ball a plunger, *c*, in the form of a solid or rigid spheroidal protuberance. The exterior of the ball is provided at the under side of the ring *r* with a ledge or shoulder, *s*, 30 which by its contact with said ring serves to retain the ball in its seat on the holder.

The described atomizer or sprinkler is operated by pressing the plunger *c* onto the ball, so as to collapse the latter; and by submerg-

ing the ball in this condition under the water, 40 and while holding it there releasing the ball from the pressure of the plunger, the water is thus allowed to enter the ball through the port or inlet *b* until the ball becomes filled. Is is then ready for use. The sprinkling being effected by pressing the plunger down onto the ball, the plunger first coming over the port *b*, and thus closing it, the compression of 45 the ball forces the water in a fine spray through the perforations *a a* thereof.

Having described my invention, what I claim as new, and desire to secure by Letters Patent, is—

1. The within-described sprinkler, consisting of a holder having a ring, a hollow elastic 55 ball secured in said ring, and having one of its protruding sides provided with perforations for throwing a spray, and the other protruding side provided with an induction-port, and a plunger connected with the holder and adapted to compress the ball and simultaneously close the induction-port thereof, substantially as set forth.

2. In combination with the holder provided with a ring, the compressible hollow ball seated in said ring, and provided underneath the same with a ledge or shoulder, substantially as and for the purpose shown and set forth.

In testimony whereof I have hereunto signed my name and affixed my seal, in the presence 70 of two attesting witnesses, at Pittsfield, in the county of Berkshire, in the State of Massachusetts, this 9th day of May, 1883.

MOSES GOLDMAN. [L. S.]
